EMASCULATOR

Dale B. King, Piru, Calif.

Application May 31, 1938, Serial No. 210,954

3 Claims. (Cl. 128—306)

This invention relates to that type of instrument for emasculating animals wherein emasculation is effected by severing the spermatic cord or by crushing a section of the cord so completely that nature will not renew the functioning thereof, this being done without the use of a knife and without it being necessary to cut open the pouch wherein the testicles are contained. A result of crushing or severing the spermatic cord as above stated, is to cause the testicles to atrophy, a permanent sterilizing consequently being effected of the animal upon which the operation is performed.

It is an object of this invention to provide an emasculating instrument of the above stated kind wherein the cutting or crushing action will be confined as nearly as possible to the spermatic cord itself, instead of there also being a crushing and bruising of so much of the tissue adjacent to the cord as it has heretofore been found necessary to damage seriously by the use of certain animal castrating instruments now on the market.

Another object of this invention is to provide a castrating implement which will be more easily operable by reason of the fact that the crushing or destroying action of the tool is concentrated more closely upon opposite sides of the particular area of the scrotum which overlies the spermatic cord, instead of being distributed over a larger area of the portion of the reproductive organs being operated upon.

Yet another object of the invention is to provide a castrating instrument which can be operated in a more accurate and dependable manner by reason of being furnished with an improved means for holding the spermatic cord in proper position for being operated upon until the gripping action of the instrument is applied to it with a sufficient force to sever or crush a section of it to the extent necessary to perform an efficient castration.

Other objects, advantages, and features of invention will hereinafter appear.

Referring to the accompanying drawing, which illustrates what is at present deemed to be a preferred embodiment of the invention:

Fig. 1 is a perspective view of the complete instrument showing the gripping jaws thereof in the open position.

Fig. 2 is a view thereof partly in side elevation and partly in longitudinal mid-section, the handle portions being broken away in order to contract the view, parts are also broken away to show underlying parts more clearly. The jaws are open in this view and between them is shown

in section of a lateral portion of an animal's scrotum and wherein the spermatic cord is being held opposite to the part of the instrument which is constructed for severing it.

Fig. 3 is a view similar to Fig. 2 except that the instrument is shown in the position which it assumes at the completing of the emasculating operation.

Fig. 4 is a sectional detail taken on line 4—4 of Fig. 3.

Referring in detail to the drawing of stationary jaw 5 is directed angularly from the shank 6, of which it forms a part. The inner end portion 7 of said shank is deflected toward the same side of the shank portion 6 as is the jaw 5, thus providing proper guiding means for the movable jaw assembly 8 which is furnished with a guide sleeve or band 9 that fits around the straight portion of the shank 6 with a working fit.

The deflected portion 7 of said shank is continued at its inner end into the arm or handle 10. With said arm 10 cooperates a movable jaw arm 11 which is pivotally connected at 12 with the deflected shank portion 7. The short end of the lever afforded by said arm 11 is pivotally connected with one end of a link 13 by means of a pivot 14, this portion of the arm 11 being shown reinforced and bifurcated by reason of having secured to opposite sides of it the strips 11a. At its opposite end said link is shown bifurcated, the bifurcations 15 thereof passing astride an ear 16 carried by a sliding plate 17, a pivot 18 serving to connect the bifurcated end of said link with said ear.

Describing more fully the plate or slide 17, the sleeve or loop 9 has its side portions extended to form parallel guide plates 20 between which said slide 17 has a working fit, a spacing strip 21 being fitted between the end portions of said plates 20 and held in this position by the rivets 22 in order to complete the guiding means for said slide 17. Said spacer strip 21 is furnished with a projecting end portion 23 positioned to aid in the emasculating operation as will be more fully understood when the operation of the device is described.

The slide 17 is L-shaped, having one limb 17a which extends along the inner edge of the spacing strip 21 and having another limb 17b which approximately contacts with the adjacent edge 50 portion of the jaw shank 6. Said limb 17a has a longitudinal guide slot 25 along approximately its mid-width, and a guide pin 26, the end portions of which are fixed in the plates 20, extending through said slot. The jaw edge of said limb 55

17a is rounded as shown at 17x in Fig. 4 to give it more of a cutting action.

The plates 20 also have secured between them an auxiliary jaw member 27 consisting of a block 5 or spacing plate a part of which projects from between said plates toward the stationary jaw 5. Said member 27 is shown held in place by rivets 28 which are carried by the plates 20.

The addition of said jaw block 27 to the structure 10 previously described results in a rectangular space 29 being formed within the angle demarcated by the arms 17a and 17 of the slidably L-shaped jaw member 17. Within said space is placed a laminated S-shaped leaf spring 30 which acts 15 between the arm 17b and the auxiliary jaw member 27.

Through the portion of the lever arm 11 which is reinforced by the strips 11a, extends an adjustable stop screw 31 furnished with a milled head 20 32. Said screw is adjusted to arrest the swing of the levers 10 and 11 toward each other when the cord-severing operation has proceeded to a completion, so far as obtaining the desired result is concerned.

25 In Fig. 2 a portion 35 of an animal's scrotum is shown, the operator having brought the cord 36 into a position opposite to the gap between the auxiliary jaw portions 26 and 27 and in Figs. 3 and 4 the jaw elements are shown as closely 30 approximated as is necessary to successfully perform the operation, the stop screw 31 preventing further crushing of the tissues, which would be unnecessary and undesirable.

It will be seen that the working face of the 35 movable jaw assembly has a length considerably greater than its width, and that the end portions of said face are formed by the jaw elements 23 and 27 that are yieldable in relation to the intermediate jaw members 17.

40 In the operation of the device, to castrate a bull, for example, the animal is first thrown or else placed in the proper handling stocks. The operator will then take the scrotum in hand and while holding it in such a manner as to bring one 45 of the spermatic cords near to an edge portion of the sac will insert such edge portion thereof between the opened jaws of the instrument and close to the body of the animal. Then while the spermatic cord is kept opposite to the space between the jaw elements 23 and 27 of the movable 50 jaw assembly, the movable lever arm 11 is operated thus causing the movable jaw assembly to approach the stationary jaw assembly. As this jaw assembly approaches the stationary jaw, such 55 jaw elements 23 and 27 contact with the scrotum at each side of the spermatic cord and under the urge of spring 30 will contact firmly with the tissue of the scrotum before, under a further movement of said arm 11 and the limb of the movable jaw assembly begins to move outwardly in relation 60 to the jaw elements between which it is located. Hence the section of the spermatic cord opposite to the movable jaw assembly will be efficiently held in the proper position for having a section 65 of it crushed by the jaw element 17a when the lever arm 11 is moved thru the remaining portion of its travel.

However, the final closing movement of said 70 arm 11 will not crush the tissue of the scrotum at either side (upper or lower side as viewed in the drawing) of the spermatic cord, for the stop screw 31 will be set to arrest the closing movement of the movable jaw assembly element 17a just a little before it can contact with the stationary jaw, as shown in Fig. 3. The instrument 75

is then removed and reapplied to the scrotum at the opposite side thereof and the same operation is performed upon the spermatic cord of the other testicle.

It will be seen that in using this instrument the 5 tissue of the scrotum is bruised only over the two small areas where it overlies each spermatic cord. Hence emasculation is performed in as humane a manner as can be expected in using an instrument of this class. Also there is so little interference with the free circulation of blood to and from the injured area that rapid healing ensues 10 as well as a speedy atrophy of the testicles. No open wound is left, which if produced, might become infected. 15

The guide pin 26, carried by the plates 20 of the sleeve member 9 is contacted by the outer end of the slot 25 when the movable lever arm 11 is swung sufficiently far from the stationary arm 10 to retract the L-shaped jaw member 17 a 20 short distance. Then a farther swing of said arm 11 will cause said pin to retract the jaw elements 23 and 27 to the fully opened position shown in Fig. 2.

It should be understood that the present disclosure is for the purpose of illustration only and that this invention includes all modifications and equivalents which fall within the scope of the subject matter claimed.

What is claimed is:

1. In an instrument of the kind described, a stationary lever arm having a deflected end portion which forms a stationary jaw, a sleeve member having a working fit upon said lever arm adjacent to said jaw, said sleeve member comprising an elongated plate so bent at its mid-length as to provide spaced apart parallel end portions which project laterally from said lever arm in the same direction as said jaw, said projecting plate portions having secured between 35 them two spacing plates, said spacing plates being themselves spaced apart and both of them projecting beyond the side of said sleeve member which is nearest to said stationary jaw, the projecting portions of said spacing plates forming 40 auxiliary jaw elements of a movable jaw assembly, an intermediate jaw element forming part of said movable jaw assembly having a projecting limb, the working face of said intermediate jaw element reciprocating in the space between 45 said auxiliary jaw elements, spring means interposed between one of said auxiliary jaw elements and said limb of said intermediate jaw element, said spring normally yieldingly maintaining said auxiliary jaw elements in an advanced position 50 in relation to said intermediate jaw element, and a movable lever arm pivotally connected with said stationary lever arm and operatively connected with said intermediate jaw element.

2. In an instrument of the kind described, a stationary lever arm carrying a stationary jaw, said jaw having a flattened shank portion connecting it with said arm, a movable jaw assembly operatively related to said stationary jaw, said jaw assembly comprising an elongated plate 65 bent into a U-shape thus forming a loop the base portion of which fits around said shank with a working fit, an inner spacing plate secured between the side portions of said bent plate, said spacing plate having a working contact with the 70 edge portion of said shank which is opposite to the base of said loop, an edge portion of said spacing plate projecting from between the space embraced by said bent plate and toward said stationary jaw thus forming part of the working 75

face portion of said movable jaw assembly, an outer spacing plate secured between the end portions of said bent plate, said outer spacing plate likewise having a projecting portion which forms a part of the working face of the movable jaw assembly, an intermediate movable jaw element having a working mounting between said spacing plates, said jaw element having a limb directed toward the aforementioned jaw shank, a spring interposed between said limb and inner spacing plate, and a movable lever arm pivotally connected with said stationary lever arm and operatively connected with said intermediate jaw element.

15. 3. In an instrument of the kind described, a stationary jaw, a movable jaw assembly com-

prising relatively movable jaw portions, each of said jaws being mounted in a relation suited to gripping between them the spermatic cord and overlying scrotum portion of an animal to be castrated, said movable jaw portions comprising normally projecting yieldable parts positioned to straddle the spermatic cord and apply yielding pressures to the scrotum as said assembly and movable jaw portions are moved toward said stationary jaw, whereby to place the spermatic cord in position for crushing, a substantially unyieldable part intermediate said yieldable parts to apply a crushing pressure to a section of the spermatic cord, and means to operate said jaws for the intended purpose.
